UNITED STATES PATENT OFFICE.

JOHN A. PRICE, OF SCRANTON, PENNSYLVANIA.

STOVE OR RANGE.

SPECIFICATION forming part of Letters Patent No. 284,230, dated September 4, 1883.

Application filed March 26, 1883. (No model.)

To all whom it may concern:

Be it known that I, JOHN A. PRICE, of Scranton, in the county of Lackawanna and State of Pennsylvania, have invented certain new and useful Improvements in Stoves or Ranges; and I do hereby declare the following to be a full, clear, and exact description of the same, reference being had to the accompanying drawings, forming a part of this specification, and to the figures and letters of reference marked thereon.

This invention relates particularly to that class of stoves or ranges which are provided with a back plate extending above the top surface of the stove or range proper, and in which the smoke-discharge pipe is located behind such extended back plate; and it consists, primarily, in providing a shelf vertically adjustable on said extended back, and projecting laterally over the top of the stove or range proper.

It further consists in constructing the shelf so that it may be laterally extended in order to project more or less over the stove or range top, and, finally, in novel means for raising and lowering the shelf.

In the accompanying drawings, Figure 1 represents a front view of a range with my improvements applied thereto. Fig. 2 is a sectional view of the same, taken on the line *x x*, Fig. 1.

Similar letters of reference in the several figures indicate the same parts.

A represents the top of the range; B, the back plate, preferably permanently connected thereto and extending above the top of the range, as shown. From an opening, C, in the top of the range, through the extended back plate, and to the rear thereof, extends a box or flue, D, which serves to conduct the smoke, &c., discharged through the opening C behind the back plate, whence it is allowed to pass off up a flue, E, connected to the bar or flue D at *d*, as shown in Fig. 2.

This construction and arrangement of flues, it will be observed, leaves the front face of the extended back entirely unobstructed, and permits of the attachment of a shelf, F, extending from side to side of the range, and of equal width throughout its length, no cutting away being required, as would be the case if the

smoke-pipe passed up in front of the back plate, as ordinarily.

I preferably arrange the shelf F with relation to the back plate so that it may be vertically adjusted on the latter, and thus enable it to be brought down nearer to or farther from the top of the range. One mode of effecting this adjustment is to mount the shelf upon racks G G, which play up and down in guides H H on the rear side of the back plate, and are raised or lowered simultaneously by means of pinions I I, mounted on a cross-shaft, K, that extends from side to side of the range, and adapted to be operated by means of a crank, L, applied to either end, as shown in Fig. 1.

A ratchet and pawl, or other contrivance, M N, is provided to prevent the back rotation of the shaft K, and to maintain the shelf in any position to which it may be adjusted.

When the top of the stove is occupied by a clothes-boiler, or a large pot or other utensil, the shelf is adjusted up to its fullest extent out of the way; but ordinarily it may be adjusted down more or less close to the range-top, and sustain plates, cooked dishes, or other articles desired to be kept hot.

By preference I make the shelf laterally extensible, so that it may be projected more or less over the range-top, as desired. One way of accomplishing this is to form it in two sections or parts, the outer section, O, being hinged to the inner section, as shown in Fig. 2, and one of the parts or sections being provided with a projection, P, which, when the outer section is turned down, serves to support it in a horizontal position. By this provision the capacity of the shelf can be varied.

I do not confine myself to any particular form of shelf, as that may be changed to suit the fancy of the constructor.

Any device or construction herein shown or described and not herein particularly claimed I reserve the right to claim in another application or applications.

Having thus described my invention, I claim as new—

1. The combination, with a stove or range having a back plate extending above its top, of a shelf vertically adjustable on said extended back and projecting laterally forward

over the stove or range top, substantially as described.

2. The combination, with a stove or range having a back plate extending above its top, 5 and a smoke-discharge pipe behind said extended back, of a vertically-adjustable shelf projecting from the front of the extended back, and racks and gears for raising and lowering said shelf, substantially as described.

10 3. The combination, with the extended range-

back, of the shelf projecting from the front thereof, said shelf consisting of an outer section hinged to the inner section, and held in horizontal position, when swung down, by means of a projection on one of said sections, 15 substantially as described.

JOHN A. PRICE.
